UNITED STATES PATENT OFFICE.

FREILING C. FOSTER, JR., OF CHICAGO, ILLINOIS, ASSIGNOR TO FREILING C. FOSTER, OF CHICAGO, ILLINOIS.

PERFUME-DISPERSER.

1,285,101.

Specification of Letters Patent. Patented Nov. 19, 1918.

Application filed October 14, 1916. Serial No. 125,566.

To all whom it may concern:

Be it known that I, FREILING C. FOSTER, Junior, a citizen of the United States, residing at Chicago, in the county of Cook and 5 State of Illinois, have invented a certain new and useful Improvement in Perfume-Dispersioners, of which the following is a specification.

My invention relates to a perfume dis- 10 perser, and I have illustrated it in connection with an automobile, though of course it could be used in any other position. One form of the invention is illustrated in the accompanying drawings, wherein—

15 Figure 1 is a side view of a portion of an automobile showing my device in position on the mud guard;

Fig. 2 is a longitudinal section through the disperser;

20 Fig. 3 is a rear elevation;

Like parts are indicated by similar letters in all the figures.

A is an automobile wheel.

25 B, B, the mud guard, to which the disperser is secured by means of the screw bolt C, nut C¹, and shoulder C².

D is a frame annular in shape.

E is a cup-like structure closed by the end F, but open at G. It is held in position by 30 ribs H, H, which are connected to the cup and the inside of the rim-shaped frame. The cup E is provided with a hole J, and is filled or lined with any desired material, as, for example, an absorbent lining K. It is

35 provided with a perforated closure L, and a perforate cap M. Between the closure and the cap is located a small fan N, and within the annular frame is a large fan O. These two fans are mounted on the shaft P. This 40 shaft is shouldered at Q, R, to prevent its motion toward the right, and the hub S of the fan N bears against the closure L to prevent its motion toward the left.

I wish my drawings to be taken as dia- 45 grammatic although it does present an operative structure. I do not wish to be limited to the precise form, arrangement, structure and shape of the several devices or parts which I have shown.

50 The use and operation of my invention are as follows:—

It will be understood that my invention broadly speaking consists in means for dispersing perfumes by the action of a current

of air, and it particularly comprises means 55 wherein one fan driven apparatus furnishes the motor power to drive another, which in turn propels the current of perfumed air in the desired direction. The disperser could be placed in any desired position. I have 60 suggested its being placed at the farther end of an automobile, and for convenience, of placing it on the mud guard. That is, when the automobile is in motion the motor fan will be driven by the current of air and the 65 dispersing fan will be driven by its connection from the motor fan. The air will be drawn in through the hole in the top of the cup, and will be charged with perfume, and then by the distributing fan such perfumed 70 air will be discharged and distributed toward the rear.

The cup constitutes a mixing device whereby the air and perfume are mixed. The large fan is a motor which operates the 75 mixer and also the distributor. The small fan is the distributor, which, by moving the current of air, causes the mixer to operate and also to mix air to be distributed.

In my preferred form my device is adapt- 80 ed to be used for the impregnating of air with perfume, but it is obvious that the device would be operated for other purposes, and that it must not and cannot be limited in its scope to a mere perfume disseminator. 85 The device is really a vaporizer adapted to vaporize any liquid and mix it with the air, and then diffuse it or discharge it.

Attention is called in this connection to the fact that certain liquids are difficult to 90 vaporize, but that they vaporize much easier under low absolute pressure conditions. That is to say, they vaporize at a pressure less than atmospheric much more easily than they vaporize at atmospheric pressure, and 95 my device is so arranged to provide a minus pressure in the mixing chamber, which minus pressure will assist in the vaporizing of the liquid. Reference to the drawings will show that the pump fan is operated to 100 draw air out of the mixing chamber through the perforated partition, but that air is allowed to enter the chamber only through the single small opening in the wall thereof. This small opening is much smaller than the 105 effective opening of the passages through the partition through which the air is discharged, so that when the fan is operated,

the air will be sucked out more rapidly than it can at atmospheric pressure enter through the hole. The result will be a minus pressure in the mixing chamber, greater, that is to say, more and more below atmospheric pressure as the speed of the fan increases. Thus if the perfume or medicine or other liquid wished to be vaporized is hard to vaporize, the speed of the fan will be increased, the minus pressure increased, and the vaporization will go on in the usual way.

I claim:

1. In a perfume distributor the combination of a motor fan with a distributor fan connected therewith and driven thereby, and an air and perfume mixer between them.
2. In a perfume distributor the combination of a motor fan with a distributor fan connected therewith and driven thereby and an air and perfume mixer between them provided with an air inlet and an air outlet in the mouth of which is situated the distributor fan.
3. A vaporizer comprising a cylinder substantially closed at one end and on the sides and open at the other end, a liquid supply source contained within the cylinder, a perforated partition in the cylinder between its open end and its closed end, the liquid supply source being located between the partition and the closed end of the cylinder, an air intake passage in the wall of the cylinder communicating with the part of the cylinder containing the source of liquid supply, a perforate wall closing the open end of the cylinder, a suction fan located within the open end of the cylinder outside of the apertured partition wall, and means for rotating the fan to draw air out of the chamber, the effective area of the perforations in

the partition wall being greater than the area of the intake passage.

4. A vaporizer comprising a mixing chamber, a motor fan mounted for rotation upon an axis passing through the mixing chamber, a shaft carrying said fan, a suction fan carried by the shaft, the vanes of the motor fan extending outwardly beyond the mixing chamber, a source of liquid supply within the chamber, a suction fan mounted upon the motor fan shaft and adapted to be driven thereby, and discharge passages leading from the chamber to the fan, an intake passage discharging into the chamber, the respective area of the passage leading from the chamber to the fan being greater than the area of the intake passage.

5. A vaporizer comprising an annular frame, a mixing chamber, radial arms adapted to support it in a central position on one side of the frame, a motor fan rotatably mounted within the frame, having the effective ends of its vanes extending outwardly beyond the mixing chamber, the chamber being open on one side, a perforate wall closing such open side, a liquid distributing member within the chamber, a suction fan in the open side of the chamber, a driving connection between it and the motor fan, an air inlet passage in the wall of the chamber having its effective area smaller than the effective area of the opening in the perforated partition.

In testimony whereof, I affix my signature in the presence of two witnesses this 10th day of October 1916.
